GALVANIC TAIL TORPEDO

John Hays Hammond, Jr., Gloucester, Mass.

Application July 6, 1932, Serial No. 621,036

16 Claims. (Cl. 114—23)

This invention relates to the control of self propelled moving bodies, and more particularly to a new and improved means for controlling the action of a torpedo.

5 The invention provides a control device which becomes effective when the torpedo misses its objective and operates to redirect the torpedo for producing a hit.

For this purpose an antenna of copper wire is 10 trailed behind the torpedo in a position to contact with the hull of the target ship should the torpedo pass in front thereof. The steel hull, contacting with the copper wire, produces a galvanic action which is utilized for redirecting the 15 torpedo toward the ship from the opposite side.

The invention also provides means for causing the torpedo to follow a predetermined irregular course after the tail has contacted with the hull of an enemy ship. Means may also be provided 20 for readily varying said predetermined course prior to the launching of said torpedo.

Means are further provided to prevent the operation of the redirecting mechanism until the torpedo has travelled a predetermined distance or 25 until a predetermined time has elapsed after launching.

The invention also provides means for presetting the redirecting mechanism so that the torpedo will turn in the same direction as the enemy 30 ship is traveling.

The invention also consists in certain new and original features of construction and combinations of parts, hereinafter set forth and claimed.

Although the novel features which are believed 35 to be characteristic of this invention will be particularly pointed out in the claims appended hereunto, the invention itself, as to its objects and advantages, the mode of its operation and the manner of its organization, may be better understood 40 by referring to the following description taken in connection with the accompanying drawings forming a part thereof, in which

Figure 1 is a sectional view of a portion of a 45 torpedo embodying features of the present invention;

Figure 2 is a section taken on line 2—2 of Figure 1.

Figure 3 is a sectional view of the tail of the 50 torpedo.

Figure 4 is a sectional view similar to Figure 1 of a modified form of the invention.

Figure 5 is an enlarged view of part of the 55 mechanism shown in Figure 4; and

Figure 6 is a diagrammatic illustration of the

course of the torpedo under the influence of the control device.

Like reference characters denote like parts in the several figures of the drawings.

In the following description and in the claims 51 parts will be identified by specific names for convenience, but they are intended to be as generic in their application to similar parts as the art will permit.

Referring to Figures 1 to 3, there is shown a 10 water borne body forming a carrier of explosives, having a water-tight torpedo hull 10, and arranged to be propelled by a pair of propellers 11, 11. The propellers 11 are mounted on a pair of concentric shafts, including an outer shaft 12, 15 and an inner shaft 14. The shafts 12 and 14 are directly connected to a driving means 15. A gear 17 is keyed to the outer shaft 12 for operative engagement with gears 18 and 19 to cause rotation of shafts 20 and 22, as will hereinafter be de- 20 scribed.

Horizontal rudders for varying the direction of movement of the torpedo about its horizontal transverse axis may also be provided in a well-known manner, but as such rudders and depth 25 control devices for controlling the same are well-known, it is thought that a more detailed description thereof is unnecessary herein.

For varying the direction of movement of the torpedo about a vertical axis so as to steer the 30 torpedo in azimuth there is provided a pair of blade rudders 30 pivotally mounted upon a pair of rotatable vertical rudder posts 31, whereby the rudders 30 can be moved relative to the torpedo to control the direction of movement there- 35 of. The rudder posts 31 are shown rigidly connected by a yoke 32 which may be shifted according to requirements by a connecting rod 33 having one end pivotally connected thereto. The other end of the connecting rod 33 is pivotally 40 secured to a piston rod 34 of a piston 35 which is mounted for reciprocating movement in a cylinder 36. This cylinder is the steering cylinder of a standard torpedo steering mechanism and is controlled in a well-known manner by the 45 usual gyroscopic apparatus 37, which need not be more fully described herein. Attention is called to Patent No. 1,857,150, dated May 10, 1932, and issued to John Hays Hammond, Jr., for a more complete disclosure of the construction and 50 operation of this apparatus.

The cylinder 36 is supplied with compressed air from a pipe 38, the other end of which is connected to a valve 39. This valve is provided 55 with two pistons, 41 and 42, mounted on a valve

stem 43 to the ends of which are secured collars 44 and 45. Between the collar 45 and the valve 39 is a spring 46. The valve 39 is supplied with compressed air from any suitable source not shown by means of a pipe 47.

The valve 39 is connected by means of a pipe 48, to a rotary valve 51. This valve is provided with an exhaust port 52 and is connected by means of two pipes 53 and 54 to two cylinders 55 and 56, which are provided with pistons which are connected by piston rods to two arms 57 and 58. These arms are separated by means of a compression spring 59. Secured to the connecting rod 33 is a pin 61 which, when the rudders 11 are in the central position, is located midway between the arms 57 and 58. The spacing between the ends of these arms is such that the pin 61 will be free to move when the rudders are thrown over hard, either to port or starboard, by the ordinary gyro mechanism, as explained above.

Rotatably mounted between the arms 57 and 58 is a cam 62, which is secured to a shaft 63. (See also Figure 2.) One end of the shaft 63 is splined at 263 and is provided with a cone clutch element 64 which is slidably mounted on this shaft and is rotatable therewith. The cone clutch element 64 engages a stationary cone clutch element 65, forming in combination therewith, a water-tight bearing. The stationary cone clutch element 65 is recessed as at 66 and is secured in a fixed position to the hull 10. The outboard end of the movable clutch element 64 is provided with a pointer or indicator 67 and terminates in a square end 68, for engagement by a socket wrench or other adjusting tool. A compression spring 69 is positioned on the shaft 63, between the cam 62 and the clutch member 64 and serves to maintain the movable clutch member 64 in intimate contact with the stationary clutch member 65. The arrangement is such that the pointer 67 indicates on the outside of the torpedo the position of the cam 62.

The collar 45, on valve stem 43, (Figure 1) is normally engaged by a trip member 71, which forms the core of a solenoid 72 and is held in the position shown by means of a spring 73. The solenoid 72 is in a circuit, including a battery 74, and the front contact 75 of a relay 76. The solenoid 72 is connected by a conductor 77 to a time switch 78, and by a branch conductor 79 to a distance gear switch 81.

The time switch 78 comprises a shaft 82 driven by a clockwork mechanism. To this shaft is adjustably attached a contact arm 83, which at suitable times engages a contact 84, which is mounted on, but insulated from, the casing of the time switch 78. The clockwork mechanism in the casing 78 is held in the inoperative position by means of a spring pressed trip member 84. This trip is normally held in this position by means of a latch 85, which is made of spring material, and is secured at its upper end to the casing 78. Secured to the lower end of this latch is a heavy weight 86. The contact 83 is connected by a conductor 87 to the armature of the relay 76, and by a branch conductor 88 to the distance gear switch 81.

The distance gear switch 81 comprises two flexible contacts 91 and 92, which are connected to conductors 79 and 88 and which are secured to, but insulated from, a shaft 93. This shaft passes through a water-tight bearing 94, and at its upper end is provided with a pointer 95 and a square head 96, which may be engaged by an adjusting tool; thus the distance switch 81 may

be rotated to any desired position, which is indicated by means of the pointer 95 on a suitable scale. The contact 92 is provided with a button 97 of insulating material which engages a circular cam 98. This cam is driven at a very slow rate of speed from the shaft 20, by means of reduction gearing 99.

The relay 76 (Figure 1) is connected in a circuit including a battery 101, and the front contact 102 of a very sensitive D. C. relay 103. One side of the winding of this relay 103 is connected to a conductor of copper wire, or other suitable material 104, which passes through a pipe 105 to the exterior of the torpedo. This wire is covered with insulation from the relay to a point just behind the tail of the torpedo and from there on extends as bare copper wire for a suitable distance behind the torpedo.

The other side of the winding of the relay 103 is connected by an insulated conductor 105 to a copper grid 106, which is mounted in, but insulated from a water-tight compartment 107, which is in communication with the water in which the torpedo is running by means of openings 108. The grid 106 may be of any suitable material, but copper has been found to be the most satisfactory.

Shortly before the torpedo is fired, the distance gear is set by turning the shaft 93, a given amount as indicated by the pointer 95. This is done by the use of a socket wrench or adjusting tool which fits over the square end 96 of the shaft 93. This distance is considerably less than the estimated range of the enemy. In this way, the distance gear switch 81 is moved to a given position with respect to the cam 98. The angular distance between the cam projection 98, and the button 97, is proportional to the distance which the torpedo will travel before the distance gear switch 81 is closed.

The time switch 78 is then set by turning the contact arm 83 to the desired position as indicated on the scale 80. This position is determined by the length of time which it is desired to have elapse between the firing of the torpedo and the time at which the control mechanism becomes operative.

If the enemy is moving to the left, as shown in Figure 6, the rotary valve 51 is turned to the position shown in Figure 1, by means of a suitable tool inserted in the square-shaped recess 50. An adjusting tool is placed on the square end 68 of the clutch element 64. This is then pressed in slightly to release this element from the stationary clutch element 65. The cam 62 is then rotated to any desired position as indicated by the pointer 67. The tool is then removed, allowing the clutch element 64 to engage the stationary clutch element 65 under the action of the spring 69, thus securely holding the cam 62 in the position which it is in at that time.

When the torpedo is fired, the contact wire 104 is unreeled from a detachable reel or other suitable means not shown. The weight 86 of the time switch 78 is moved rearward with respect to the torpedo, due to its inertia, thus releasing the trip 84 which is moved upwardly under the action of its spring. This releases the clock-work mechanism, thus starting the contact arm 83 rotating. After the lapse of the predetermined interval of time, the contact arm 83 will engage the contact 84, thus putting the circuit through the solenoid 72 into an operative condition.

As the torpedo progresses, the shaft 20 is rotated by means of gears 17 and 18, thus causing

the cam 98 to be slowly rotated by means of the reduction gearing 99. This continues until the torpedo has traveled the distance set on the distance gear. At this time, the projection of the cam 98 will engage the button 97, thus lifting the contact 92 into engagement with the contact 91.

5 It is thus seen that the solenoid 72 is maintained in an inoperative condition until either the distance gear or the time switch operates to put it into an operative condition. This is done so that the solenoid 72 will be maintained in an inoperative condition until it has reached the proximity of the target, thus preventing the premature operation of the control mechanisms, due to the 10 shock of launching, etc.

15 During its run, the vertical rudders 30 of the torpedo are controlled in a well-known and standard manner by means of the steering cylinder 36, the action of which is controlled by the gyroscope 20 37. The torpedo then runs under the control of the gyroscope until it reaches the enemy line.

25 In case it should fail to strike a ship, but should pass in front of it, the hull of the enemy's ship will contact the bare copper wire 104. This will cause a galvanic action to be set up between the metal of the ship, the wire 104, the grid 106 and the sea water, which causes a flow of current through the sensitive relay 103. This will be sufficient to operate this relay, thus energizing 30 the relay 76 which is thereby operated and in its turn energizes the solenoid 72. This will cause the core 71 of this solenoid to be moved downwardly, thus moving out of engagement with the collar 45. This allows the valve stem 43, 35 together with the pistons 41 and 42 to be moved to the right under the action of the spring 46.

40 This will shut off the supply of compressed air to the pipe 38 and will connect this pipe to the atmosphere. At the same time compressed air will be supplied to the pipe 48. This air then passes through the rotary valve 51 to the pipe 54, and thence to the cylinder 56. This causes the arm 58 to be moved to the left until it engages the face of the cam 62. The lower end of this arm will engage the pin 61, thus moving the rod 33 to the left, and thereby turning the rudders 30 to port, to cause the torpedo to be steered to the left, as seen in Figure 6.

45 The amount these rudders are turned is dependent upon the position of the cam 62. If this cam is turned only slightly from the position shown in Fig. 1, the rudders will be thrown nearly hard over, thus causing the torpedo to travel in a small circle, as shown by the dotted line 111 of Figure 6. If the cam 62, however, has been turned a greater amount, the rudders 30 will be prevented from being thrown so far over and the torpedo will describe a larger circle as shown by the dot and dash line 112 of Figure 6. It is thus seen that the torpedo can be caused to describe a circle of any desired diameter, by means of turning the cam 62 through the proper angle. If the torpedo should miss the enemy and pass in front of it, it is thus seen that it will start travelling in a circle in the path of the enemy's ship, thus giving the torpedo one or more chances of striking the enemy's ship, after the first miss. In this way, the effectiveness of a torpedo is considerably increased.

70 If the enemy is moving to the right, the rotary valve 51 is turned through a quarter revolution from the position shown in Fig. 1, so that when an enemy's ship contacts with the wire 104, compressed air will pass through the pipe 53 and thus 75 to the cylinder 55, which will cause the arm 57

to be moved to the right, an amount dependent upon the position of the cam 62. The arm 57 will then engage the pin 61, thus causing the rudders 30 to be turned to starboard, an amount dependent upon the position of the cam 62. The 5 torpedo will then circle to starboard instead of port. This cam is so shaped that, when it is moved to the desired position, the rudders 30 will be turned through equal angles to port or starboard, depending on the position of the rotary 10 valve 51.

In the modified form of the invention, shown in Figure 4, the mechanism is similar to that described in Figure 1, up to and including the rotary valve 51 which in this case is connected by 15 the two pipes 53 and 54 to the opposite ends of a cylinder 116. The piston 117 of this cylinder is connected to a rod 118, to which is attached a pin 119, which engages a slot 121 in the end of an arm 122. This arm is pivoted at 123 to the frame 20 124. The other end of the arm 122 is provided with a grooved projection 125 which normally engages a pin 126, secured to an arm 127. This arm is pivoted at 128 to the frame 124.

The upper end of this arm 127 is yoke-shaped 25 and provided with two oppositely disposed pins 129, which engage a slot 131 in a bevel pinion 132. This pinion is splined to a shaft 133, which forms part of the reduction gearing 99, and is so arranged that the pinion 132 may slide longitudinally of this shaft, but cannot rotate with respect to it. Mounted on the shaft 133 between the pinion 132 and the frame 124 is a compression spring 134.

30 Located adjacent to the pinion 132 is a bevel gear 135, secured to the end of a shaft 136, which is rotatably mounted in the frame 124. A collar 137 is pinned to the shaft 136. The lower end of this shaft is square-shaped and is also threaded to receive a nut 138 which clamps a box cam 40 139 to the shaft 136. This cam is provided with an irregularly shaped groove 141. (See Fig. 5.).

35 Located in the groove 141 is a roller 142 which is rotatably mounted on the end of an arm 143. Pivoted to the other end of this arm is a link 45 144, the other end of which is provided with a pin 145 which slides in a slot 146, provided in a member 147. This member 147 is pivoted at 148 to the frame 124. The lower end of the member 147 is provided with a slot 149 which engages 50 the pin 61, secured to the connecting rod 33. Connecting the end of the piston rod 118 to the link 144 is a link 151.

55 The operation of the modified form of the invention shown in Figure 4 is similar to that described in connection with Figures 1 to 3, up to and including the rotary valve 51, so that when the tail 104 is engaged by the hull of the enemy's ship air will pass through this valve to the pipe 53 and thence to the upper end of the cylinder 116, causing the piston rod 118 to be moved downwardly. This causes the grooved projection 125 to be moved out of engagement with the pin 126, thus allowing the arm 127 to be rotated in a counterclockwise direction under 60 the action of the spring 134. This causes the pinion 132 to mesh with the gear 135 and, as this pinion is being slowly rotated by means of the reduction gearing 99, it will cause the gear 135, together with the shaft 136 and cam 139 to 65 70 slowly rotate.

At the same time, the link 151 will be moved downwardly causing the link 144 to be rotated in a counterclockwise direction, about its right-hand end thus causing the pin 145 to slide down 75

to the bottom of the slot 146. The pin 145 is held at the bottom of the slot 146 by means of the air pressure in the cylinder 116. This motion causes the member 147 to be rotated in a 5 clockwise direction about the fixed pivot point 143 as the radius of curvature of the left-hand side of the slot 146 is less than the length of the link 144. This operation causes the rod 33 to be moved to the left which, as described in connection with Figures 1 to 3, causes the vertical 10 rudders 30 to be turned to port.

As the cam 139 slowly rotates, the roller 142 will move in the direction of the arrow in the slot 141 (see Figure 5). As it does so, the arm 143 will be slowly moved back and forth to follow the configuration of the slot 141. This, by means of the link 144 and member 147 causes the rod 33 to be moved in a similar manner, thus causing the vertical rudders 30 to be slowly oscillated 15 in a manner determined by the shape of the cam slot 141. It is thus seen that by making this slot any desired shape, it is possible to cause the torpedo to follow a predetermined course as shown by the full line 152 in Figure 6.

The part of the groove 141 indicated by the 20 numeral 153 would cause the rudders to be held hard over to port, thus causing the torpedo to follow the arc of the circle 154. The section of the groove, 155, would cause the torpedo to follow the straight section of the course 156. The section of the groove, 157, would throw the rudders part way over to port, thus causing the torpedo to follow the large arc 158, and the section 25 of the groove 159 would cause the rudders to be thrown to starboard, thus causing the torpedo to follow the arc 161.

If the officer in charge of torpedo firing decides to have the torpedo follow a different predetermined course, he can do so by removing the 30 nut 138, and taking off the cam 139 which can then be replaced by a new cam with a different shaped groove. It is possible, therefore, to have a great number of different shaped cams available for the torpedoes, so that the enemy will 35 have no idea what sort of a course the torpedo will follow, after the tail has been contacted by an enemy ship.

If the enemy is moving from left to right, the rotary valve 51 is turned a quarter of revolution, as already described, so that when air is admitted to the pipe 48, the link 144 will be raised thus moving the pin 145 to the upper end of the slot 146, which will cause the member 147 to be rotated in a counter-clockwise direction, thus 40 moving the rod 33 to the right and turn the rudders 30 to starboard. The motion produced by the cam 139 will then be reversed so that the torpedo will follow a course similar to 152, but in the opposite direction. It is thus possible 45 to use the same cam whether the enemy is approaching from the right or from the left, as by merely setting the rotary valve in the opposite site position the course followed is reversed.

Although only a few of the various forms in 50 which this invention may be embodied have been shown herein, it is to be understood that the invention is not limited to any specific construction, but might be embodied in various forms 55 without departing from the spirit of the invention or the scope of the appended claims.

What is claimed is:

1. In a direction control system, the combination of a movable body, steering means for said 60 body, means including a cam automatically op-

erative for actuating said steering means to cause said body to travel in an irregular predetermined course and means responsive to the influence of another movable body for rendering said second means effective to actuate said steering means. 5

2. In a direction control system, the combination of a movable body, steering means for said body, means including a cam automatically operative for actuating said steering means to cause said body to travel in an irregular predetermined course, means to rotate said cam and means responsive to the influence of another movable body for rendering said second means effective to actuate said steering means. 10

3. In combination, a torpedo, a steering mechanism, control means acting on said steering mechanism including a cam rotated at a slow speed for operating said steering mechanism in a predetermined irregular manner, a metallic wire carried by said torpedo, but insulated therefrom and means initiated by the contact of said wire with a metallic hull for causing said control means to operate. 15

4. In a torpedo, a torpedo body having propelling devices thereon, a steering rudder, means 20 for adjusting the operating position of the rudder to any predetermined point between neutral and hard over to change the curvature of the path of the torpedo, and means controlled by influence of the target to operate said rudder to 25 cause said torpedo to follow the target.

5. In a torpedo, a torpedo body having propelling devices thereon, a steering rudder, a main steering device normally controlling said rudder, means for presetting the direction of operation 30 of said rudder according to the direction of movement of the target, means for adjusting the operating position of the rudder between neutral and hard over to cause the torpedo to change the curvature of its path, and means controlled 35 by the influence of the target for operating said rudder to cause said torpedo to follow the target. 40

6. In a vehicle, a vehicle body having propelling devices thereon, a steering element, means for presetting the direction of operation of said steering element according to the direction of movement of the target, means for presetting the maximum steering element movement, an auxiliary control element, and means operative 45 by the influence of the target on said auxiliary control element for operating said steering element and causing said body to execute a complete circular path in front of the target. 50

7. In a torpedo, a torpedo body having propelling devices thereon, a steering rudder, means 55 for presetting the direction of operation of said rudder according to the direction of movement of the enemy ship, means for presetting the maximum rudder movement, an auxiliary control element trailing said torpedo, and means 60 operative by the influence of the enemy ship on said auxiliary control element for operating said rudder and causing said torpedo to execute a complete circular path in front of the enemy ship. 65

8. In a torpedo, a torpedo body having propelling devices thereon, a steering rudder, a gyroscope normally controlling said rudder, means for presetting the direction of operation of said rudder according to the direction of movement 70 of the enemy ship, means for presetting the maximum rudder movement, and means controlled by the influence of the enemy ship for operating said rudder to cause said torpedo to follow the ship. 75

9. In a torpedo, a torpedo body having a pro-

5 pelling device thereon, a steering rudder, a control cam, a control element trailing said torpedo, and means controlled by the influence of the enemy ship on said trailing element for placing the rudder under control of said cam, whereby said torpedo executes an irregular path in front of said ship which is determined by the shape of the cam.

10. In a torpedo, a torpedo body having a propelling device thereon, a steering rudder, a gyroscope device normally controlling said rudder, a distance gear operated by said propelling device, a timing device started by the impulse of firing the torpedo, an auxiliary element carried by said 15 torpedo, means for presetting said distance gear to take effect at the desired point of torpedo travel, means for presetting said timing device to take effect at the desired time, an auxiliary steering device operable upon said rudder, said 20 auxiliary steering device comprising means for presetting the direction of operation of the rudder, a control cam having an irregular path, and means controlled by the influence of the target on said auxiliary element for taking the 25 rudder control away from said gyroscope device and placing it under said auxiliary steering device, said last-mentioned means being under control of both said distance gear and timing device, said control cam varying the position of the 30 rudder.

11. In a vehicle, a vehicle body having propelling devices thereon, a steering element, a main steering device normally controlling said steering element, an interval measuring device, an auxiliary element carried by said vehicle, means for presetting said interval measuring device to take effect at the desired point, an auxiliary steering device operable upon said steering element, said auxiliary steering device comprising 35 means for presetting the direction of operation of the steering element, a control cam having an irregular path, and means controlled by the influence of the target on said auxiliary element for taking the steering element control 40 away from said main steering device and placing it under said auxiliary steering device, said last-mentioned means being under control of said interval measuring device, said control cam varying the position of said steering element.

50. 12. In a torpedo, a torpedo body having a propelling device thereon, a steering rudder, a gyroscope device normally controlling said rudder, a distance gear operated by said propelling device, a timing device started by the impulse of firing the torpedo, an auxiliary element carried by said 55 torpedo, means for presetting said distance gear to take effect at the desired point of torpedo travel, means for presetting said timing device to take effect at the desired time, an auxiliary steering device operable upon said rudder, said auxiliary steering device comprising means for presetting the direction of rudder operation,

means for presetting the amount of rudder operation, and means controlled by the influence of the target on said auxiliary element to take the rudder control away from said gyroscope device and to give the rudder control to said auxiliary steering device, said last-mentioned means being under the control of both said distance gear and timing device. 5

13. In a vehicle, a vehicle body having propelling devices thereon, a steering element, a main 10 steering device normally controlling said steering element, an interval measuring device, an auxiliary element carried by said vehicle, means for presetting said interval measuring device to take effect at the desired point, an auxiliary 15 steering device operable upon said steering element, said auxiliary steering device comprising means for presetting the direction of steering element operation, means for presetting the amount of steering element operation, and means 20 controlled by the influence of the target on said auxiliary element to take the steering element control away from said main steering device and to give the steering element control to said auxiliary steering device, said last-mentioned 25 means being under the control of said interval measuring device.

14. A system for the control of moving bodies including in combination a body to be propelled, steering means thereon, means active upon said 30 steering means to cause said moving body to follow a circular course of predetermined radius, means under the action of an external body for rendering effective said second means on said first means and means to adjust said predetermined radius to any desired value to cause the 35 torpedo to take any desired path between a straight line and the minimum circular path of the moving body.

15. A torpedo comprising a body, a trailing 40 wire attached to said body, a steering device, means acting on said steering device whereby said torpedo will be caused to follow a circular course of predetermined radius, means operative upon the contact of said wire with the hull of 45 an enemy ship for causing said torpedo to follow said circular course, and means to adjust said predetermined radius to any desired value to cause the torpedo to take any desired path between a straight line and the minimum circular path of the torpedo. 50

16. In a self-propelled torpedo, devices on said torpedo controlled by proximity of the enemy ship for causing said torpedo to turn in the direction of movement of said ship, and means controlled entirely by mechanism on the torpedo itself independent of any further outside influence for causing said torpedo to repeatedly cross and recross the path to be taken by the enemy ship. 55

60 JOHN HAYS HAMMOND, JR.
